US00D899543S

(12) **United States Design Patent** (10) **Patent No.:** **US D899,543 S**
(45) **Date of Patent:** **** Oct. 20, 2020**

(54) **SKATEBOARD**

(71) Applicant: **RAZOR USA LLC**, Cerritos, CA (US)

(72) Inventor: **Ian Desberg**, Cerritos, CA (US)

(73) Assignee: **RAZOR USA LLC**, Cerritos, CA (US)

(**) Term: **15 Years**

(21) Appl. No.: **29/710,767**

(22) Filed: **Oct. 25, 2019**

Related U.S. Application Data

(63) Continuation of application No. 29/661,629, filed on Aug. 29, 2018, now Pat. No. Des. 865,096, which is a continuation of application No. 29/611,372, filed on Jul. 20, 2017, now Pat. No. Des. 827,748, which is a continuation of application No. 29/582,281, filed on Oct. 26, 2016, now Pat. No. Des. 792,931, which is a continuation of application No. 29/525,837, filed on May 4, 2015, now Pat. No. Des. 770,585.

(57) **CLAIM**

The ornamental design for a skateboard, as shown and described.

DESCRIPTION

FIG. 1 is a front perspective view of a skateboard, which embodies my design.

FIG. 2 is a front view of the skateboard of FIG. 1.

FIG. 3 is a rear view of the skateboard of FIG. 1.

FIG. 4 is a right side view of the skateboard of FIG. 1. The left side view is a mirror image of the right side view.

FIG. 5 is a top view of the skateboard of FIG. 1; and,

FIG. 6 is a bottom view of the skateboard of FIG. 1.

Broken lines are used to illustrate portions of the skateboard which form no part of the claimed design.

1 Claim, 5 Drawing Sheets
